(57) **CLAIM**

The ornamental design for a siren amplifier control panel, as shown and described herein.

DESCRIPTION

FIG. 1 is a front view of the claimed design for a siren amplifier control panel;

FIG. 2 is a rear view thereof;

FIG. 3 is a right view thereof;

FIG. 4 is a left view thereof;

FIG. 5 is a front perspective view thereof; and,

FIG. 6 is a rear perspective view thereof.

The broken lines in the drawings depict portions of the siren amplifier control panel that form no part of the claimed design.
